UNITED STATES PATENT OFFICE.

EDWIN E. SLICK, OF PITTSBURGH, PENNSYLVANIA.

DESIGN FOR A SMOKER'S SET.

Application filed November 28, 1925. Serial No. 15,570. Term of patent 14 years.

To all whom it may concern:

Be it known that I, EDWIN E. SLICK, a citizen of the United States, residing at Pittsburgh, in the county of Allegheny and State of Pennsylvania, have invented a new, original, and ornamental Design for Smokers' Sets, of which the following is a specification, reference being had to the accompanying drawings, forming a part thereof in which—

Figures 1 and 2 are perspective views of a smoker's set showing my new design.

I claim:

The ornamental design for a smoker's set, substantially as shown.

In witness whereof, I have hereunto set my hand.

EDWIN E. SLICK.
